NUT-CRACKING MACHINE

Leo J. Meyer, San Antonio, Tex.

Application April 5, 1947, Serial No. 739,598

4 Claims. (Cl. 146—12)

1

The invention relates to a nut cracking machine, and in particular to a machine which is capable of precision feeding of nuts of varying size to the cracking dies thereof which effects such variable cracking movement among the different sized nuts as to produce desired cracking without breaking the meats of the nuts.

The invention is concerned with a machine for cracking nuts generally, but is of particular utility in connection with the cracking of pecans which are known to vary widely in size, particularly in length. In any event, it is necessary, for machine cracking, either to carefully grade the nuts as to size and then use a cracking machine adjusted for a selected size or grade, or to provide coordinated feeding and cracking mechanisms capable of accurately placing the nuts of varying sizes in cracking position, and thereafter applying the proper amount of compression thereto, regardless of size, so that the cracking action may be complete, but without injuring the meats of the nuts thereby.

The present invention is concerned with the latter method of cracking nuts, and it is therefore an object of the invention to provide novel, coordinated combination of feeding and die elements so that nuts of varying sizes may be efficiently handled in a single machine.

Another object is to provide a feeding mechanism that will place a nut in cracking position for each relative reciprocation of the cracking dies.

Still another object of the invention is to provide a mechanism that will assure that a single nut only is fed to the cracking dies for each reciprocation thereof.

Still another object of the invention is to provide a mechanism of the conveyor type that will accomplish the objectives just indicated.

Another object is to provide a compensating mechanism or cracking box of improved design that automatically and simply provides desired takeup or cracking movement for various sized nuts fed to the machine.

Still another object of the invention is to provide a compensating mechanism or cracking box of simple and rugged construction that will operate efficiently and effectively throughout a long period of use.

The invention also comprehends the provision of a cracking mechanism, including a rocker which carries a locking element movable therewith, to engage and drive the cracking die a predetermined distance after such die has engaged a nut to be cracked.

2

The foregoing objects together with other objects and advantages of the invention will be more fully apparent from the following description considered in connection with the accompanying drawings in which:

Fig. 1 is a side elevational view showing one form of the invention;

Fig. 2 is an end view of the machine, portions thereof being cut away to more clearly show constructional details;

Fig. 3 is a detail showing the drive construction and is a view taken on line 3—3 of Fig. 1;

Fig. 4 is a plan view, partly in section and with parts removed, showing the cracking die assembly;

Fig. 5 is a view similar to Fig. 4, but with parts cut away and showing the relative position of parts when the locking element is in engagement with the reciprocating cracking die;

Fig. 6 is a detail view of the nut conveyor showing the relative position thereof with relation to the nut hopper and the arrangement whereby nuts are fed singly to the cracking dies;

Fig. 7 is a detail view showing the manner of securing individual nut carriers upon the chain of the nut conveyor;

Fig. 8 is an exploded view showing the component parts of a nut carrier and the elements associated therewith for integrating the carrier with the carrier chain;

Fig. 9 is a detail view showing the arrangement of the carrier guides within the nut hopper;

Fig. 10 is an enlarged detail view showing the arrangement of the rocker in the die assembly and showing the locking and guiding elements which are mounted on the rocker.

Fig. 11 is an enlarged isometric view of the die assembly;

Fig. 12 is an enlarged, isometric view of the spring holder, the rocker, and the carrier plate, including the spring holder barrel;

Fig. 13 is an enlarged isometric view of the carriage;

Fig. 14 is a plan view showing the spring holder barrel, spring holder, and locking pawl, and also showing a long pecan positioned between movable die and fixed die;

Fig. 15 is a plan view of the elements shown in Fig. 14, a short pecan being shown positioned between movable die and fixed die prior to cracking;

Fig. 16 shows the elements of Fig. 15 in cracking action;

Fig. 17 is a plan view showing die assembly

elements, including the rocker, prior to pawl and movable die locking engagement; and

Fig. 18 is a plan view of the elements of Fig. 17 showing pawl and movable die in locking engagement.

The nut cracking machine 1 embodying the invention, comprises a frame or base 2 upon which is journaled the main shaft 3 driven by a pulley 4 from a suitable prime mover such as the electric motor 5 mounted upon the platform 6 supported upon the base. Pinion 10 on the inner end of the shaft 3 driveably engages the gear 11 on shaft 12. This gear carries a wrist pin 13 upon which one end of the connecting rod 14 is mounted while the opposite end of this rod receives the pin 15 which pivotally connects the rod 14 to the carriage 36, such carriage forming part of the die assembly 16. The pin 15 also extends through the abutment 47 which has the tubular abutment 47' connected thereto as a part thereof for a purpose to be hereinbelow described. As such carriage 36 is mounted to slide longitudinally in the channel 43 of the frame 2, it can thus be said to be reciprocatory therein by virtue of its pivotal connection with the connecting rod 14. Thus upon rotation of the gear wheel 11, the die assembly 16 will be driven through a complete cycle of reciprocation for each revolution of the wheel to effect a nut cracking operation upon a nut 17 engaged between the movable die 18 of the die assembly 16 and the stationary die 19 mounted upon the frame 2.

As best seen in Fig. 3, the shaft 12 has a worm 25 thereon, meshing with the worm gear 26 on shaft 27. This shaft 27 extends forwardly into the conveyor housing to drive the lowermost of a pair of sprockets, now shown, upon which the conveyor assembly 28 is mounted. The upward flight 29 of the conveyor assembly moves upwardly within the hopper 30 to elevate nuts in succession, and to place such nuts in the cavities 31 in the carrier elements 32 as they enter the downward flight 33 of the conveyor.

The die assembly 16 comprises a carriage 36 including the base plate 37 having upstanding portions 38, 38', 39 and 39' with the gap 40 intermediate the portions 38 and 38' and the gap 41 intermediate the portions 39 and 39' to admit movement of the rocker 42 longitudinally of the carriage 36 as will be more fully described. The pin 15 is journaled in the upstanding portion 38' of the carriage 36 whereby the complete die assembly 16 is reciprocable within the channel 43 of the frame 2, as has been hereinabove explained.

Attention is directed to the fact that the movable die 18 may comprise a unitary structure although it is shown as including a die tip 18' which is removable so that replacement of the complete structure is unnecessary when wear may require replacement of such die tip.

The rear end of the die 18 is counterbored at 45 as shown in Fig. 5, to receive the compression spring 46 which engages within the tubular abutment 47' whereby the die is resiliently urged forwardly while the stop 48 upstands from the plate 37 for engagement with the shoulder 9 of the die 18 to limit forward motion of the die. A knock-out rod 50, anchored to the frame 2, extends axially through the die 18 and terminates proximate the forward end of the die so that upon retraction of the die any portion of the nut or any other foreign matter striking in the die will be removed prior to engagement of the die with a succeeding nut 17. It is also to be noted that the spring 46

is compressed when the die 18 engages a nut 17 as the die assembly 16 is moved by the connecting rod 14. Thus a predetermined force is placed upon the nut preliminary to the actual cracking operation.

Slidable longitudinally within the carriage 36 is a carrier plate 51 upon which the rocker 42 is pivoted at 52. The carriage 36 includes the base plate 37 which has the upstanding plate portion 111 thereon, adjacent to, and connected to the portion 39'. The plunger 54, shown in Fig. 10, extends from the bore 112 in the plate portion 111 to bear against the carrier plate 51. The closed tube 53 extends from the plate portion 111 and the bore 112 extends thereinto and for the length thereof to terminate at the tube end 114'. The spring 53, shown in Fig. 5, extends within the bore 112 to urge the plunger 54 against the carrier plate 51. A comparison of Fig. 10 with Figs. 4, 5, and 12, shows that the tube 53 is located directly below the abutments 47 and 47'. The arrow 55, shown in Fig. 5, indicates the oscillatory motion which can be accomplished by the rocker 42 by virtue of its pivotal mounting on the carrier plate 51. The carriage 36 has the upstanding guide 113 thereon to guide the die 18.

A stabilizing block 60 fits upon the pivot 52 on the upper side of the carrier plate 51 and slidably engages one side of the die member 18. The locking block or pawl element 61 is mounted upon a pin 62 on the rocker 42 on the opposite side of the die member 18 from the block 60. This locking block or pawl 61 is constantly urged by the indicated spring means 63 in the spring holder barrel 64, as shown in Fig. 5, such barrel 64 being connected to, or part of, the carrier plate 51. The spring means 63 is contained in a spring holder means comprising the pin 59 at one end of the spring means and the head 94 at the other end thereof. When motion of the head 94 is arrested, as will be hereinbelow explained, as the spring means 63 presses against the inner end of the pin 59, as shown in Figs. 4 and 5, the head 59' of the pin 59 will slidably engage the forward face of the pawl 61. In this manner the rocker 42 is normally held in engagement with the stop 65 on the carrier plate 51 at which time the teeth 67 on the locking element or pawl 61 are spaced sidewardly from the complementary teeth 68 on the die member 18, as shown in Fig. 4.

It is to be noted that the tooth or serrated face 67 of the locking element or pawl 61 is tapered or inclined slightly to the line of travel of the die 18 and is, therefore, in confronting parallel relation with the complementary teeth 68 on the die since such complementary teeth are formed upon a face included inwardly along the side surface of the die. This is an important feature of the invention inasmuch as it facilitates a desired mode of operation that will more fully appear hereinbelow.

The conveyor assembly 28 comprises the chain 75 which may be of conventional design, the nut carriers 32 being constructed and attached thereto in a manner now to be described. As shown in Fig. 8, each carrier comprises a pair of blocks 76 having transverse openings 77 spaced a distance equal to that between successive pins in the chain. A special link comprises side plates 78 and pins 79 of sufficient length to pass entirely through the chain and the blocks whereby the blocks are made an integral part of the chain.

The carrier body 80 and the blocks 76 may comprise an integral structure, but I prefer that these parts be made separate in order to facilitate

assembly and replacement. As shown, the body 20 has a pair of holes 31 therein to receive screws 32 which enter and are threadedly secured in the openings 33 in the block 16.

As previously indicated, each nut carrier has a cavity 31 therein open at its ends so that the die 18 may enter and move a nut along the cavity and into engagement with the stationary die 19. The cavity is also open at one side to enable entrance of a nut thereto.

Extending sidewardly from the nut carrier 32 is a projection 35 which has a nut receiving depression 36 therein. As best seen in Fig. 2, the depression 36 faces upwardly in the upward flight 29 of the conveyor and hence is adapted to receive one or more nuts as it moves upwardly from below and within the hopper 30.

As a nut carrier reverses direction from the upward flight 29 to the downward flight 32, it is intended that the nut carried thereby shall be dropped under gravity into the cavity 31 of the next preceding carrier as clearly shown in the upper portion of Fig. 2. It is also important that a single nut only be deposited in each of the cavities 31 of the nut carriers preliminary to the cracking operation. To this end each body 20 also has a fin 37 which extends transversely of the projection 35. As the carrier tilts in its movement in the upward flight 29 toward the downward flight 32, this fin tilts outwardly, as shown in Fig. 2, and serves to remove excess nuts from position upon the next succeeding carrier. In this manner there is assurance that a single nut only will be deposited in each of the cavities 31 as it moves toward cracking position.

A knockout 90 is also provided for the stationary die 19, such knockout including a rod normally spring pressed, by conventional spring means, not shown, to move to the right as shown in Figs. 4 and 5, but urged to the left by the projection 91 on the die assembly when a nut cracking operation is carried out.

The broad principle of the operation of the disclosed embodiment of the invention is believed apparent from the foregoing description. By way of reiteration and by way of further and more detailed explanation it is pointed out that a quantity of nuts are placed within the hopper 30, such nuts being restrained from passing through the lower portion thereof by virtue of the tongue 92 in the bottom of the hopper, this tongue being adapted to slidably pass through the slot 93 in the projection 35 on each of the nut carriers. As the individual carriers move upwardly, as indicated in Fig. 2, one or more nuts are elevated by each of the projections 35 in succession, the fin 37 of each carrier removing excess nuts upon the succeeding carrier as it moves toward the downward flight 32. As each carrier moves, its associated nut in alignment with the dies 18 and 19, the die assembly moves, in accordance with the above general description, and with the detailed description to be set forth hereinbelow, to engage and crack the nut, whereupon the carrier moves downwardly and away from the die assembly, and the cracked nut falls, by gravity, into a receptacle, not shown.

A consideration of Patent No. 2,264,394, issued December 2, 1941, to Leo J. Meyer for Nut Cracking Machine, when compared with the general disclosures of Figs. 4, 5, and 10, shows that the elements which differ from such prior patent, and which constitute one of the primary improvements thereover, reside in the feature whereby the pawl teeth 67 and the complementary die

teeth 68 of the present invention are tapered, whereas in the prior patent such corresponding teeth extend in parallel alignment with the longitudinal axis of the die and die assembly. The benefits obtained by this feature will be apparent when Figs. 4, 5, and 10 are considered in connection with the detailed disclosure of Figs. 11-18 inclusive, and in connection with the step-by-step operation hereinbelow narrated.

10 Prior to beginning the operation of the machine, the stop 95 in the frame 2 has been adjustably positioned so that the end 95' bears against the head 94 which is urged forwardly by the spring means 63 shown in Fig. 4. The tightening of the set screw 114 shown in Fig. 11 can thus lock the adjustable stop 95 in a pre-determined position.

As the gear 11 rotates a point is reached whereby the connecting rod 14 begins to urge the die assembly 16 forwardly. Thus the carriage 36, die 18, carrier plate 51, and rocker 42 all move together until the head 94 contacts the stop 95. This stops further forward motion of the carrier plate 51, including the barrel 64, and of the rocker 42 mounted on the carrier plate, while the carriage 36 and die 18 continue to move forward.

Then the die 18 contacts the nut 17, as the conveyor 28 is coordinated, through the transmission driving it from the same prime mover that drives the gear 11, to deliver the nut into position to be engaged by the die 18 as such die approaches the fixed die 19.

From this point the spring 46 undergoes compression as the nut between the dies resists further forward motion of the die 18 whereas the tubular abutment 47' and the abutment 47 connected thereto, through which extends the pin 15, continue to move forward with the carriage 36 to bear against the rear end of the spring 46.

Then the portion 38', which upstands from the carriage base plate 37, comes in contact with the roller or block element 57. Such roller or block 57 is pivotal upon the pin 58 which upstands from the rocker 42. The portion 38 forces 45 forwardly against the element 57, as shown most clearly in Figs. 17 and 18, the rocker 42 pivots about the pin 52, and the pawl 61 slidably forces forwardly against the head 59' of the pin 59 to compress the spring means 63. Such motion continues until as shown in Fig. 18, the pawl teeth 67 engage the die teeth 68.

At this point, which may be termed "interlockage," the die 18, carriage 36, carrier plate 51, and rocker 42 are all locked together whereby the head 94 bears against the stop 95. Stoppage could now occur, but for the provision of a means to permit the head 94 to remain stationary while permitting the carrier plate barrel 64, which receives such head 94, to move forward.

Such provision is made by providing the pin 100 in the barrel 64 and by providing in the head 94 the hole 101 through which the pin 100 extends. As shown in Fig. 5, such hole 101 is of a greater width in the direction of die assembly travel than the diameter of the pin 100, so that, while the head 94 remains stationary, the remaining parts of the die assembly may move forward to further compress the spring means 63. It is thus the spring means 63 which exerts the nut cracking pressure, while the spring 46, which originally urges the die 18 forwardly, remains in static condition after "inter-lockage."

The end of cracking is set to occur when the connecting rod 14 is just above the "dead center" position which is reached when the center of the

gear 11, the center of the wrist pin 13, and the center of the connecting rod pin 15 are in alignment. It can thus be seen that the ultimate forward position of the die assembly 16 is determined by the position of the stop 95 while the angular travel of the connecting rod during cracking is determined by the position of the movable die 18 at the instant that "inter-lockage" occurs.

The fact that the teeth 67, 68 are tapered or extended at an angle to the direction of the die assembly travel insures that such inter-lockage of die, carriage, carrier plate, and rocker will occur at an earlier stage of die assembly travel when a long nut 17 is between the fixed die 19 and the movable die 18, than when a short nut is between these dies. This is shown most clearly in Figs. 14-16 inclusive, where it can be seen that the movable die 18 in Fig. 14 is spaced further from the fixed die 19 at the point where "inter-lockage" occurs, than such movable die 18 is spaced from the fixed die in Fig. 15. Consequently, the pawl 61 engages the die 18 nearer the shoulder 9 in Fig. 14 than in Fig. 15, where a short nut 17' is shown.

It follows that a longer nut is under cracking pressure during a longer time since the connecting rod 14 goes through a longer angular travel in the cracking of a long nut than in the cracking of a short nut. However, as the resiliency of nuts vary in some proportion to length, the longer nuts can withstand the pressure of the movable die 18 for a longer period of travel before actual rupture of the nut takes place. Thus it follows that the degree of a rupture or cracking accomplished for both long and short nuts is substantially the same by virtue of the provision of the tapered teeth 67 and 68.

When the cracking operation has been completed as described, the die assembly moves outwardly to release the cracked nut which can then fall downwardly from the machine for the subsequent hulling operation. It is to be understood, of course, that as the die assembly is retracted, the knockouts 50 and 90 will operate to remove any foreign matter from within the dies 18 and 19.

It should be further noted that the spring means 63, which is compressed during the movement of the rocker 42 to effect "inter-lockage," will continue to exert a pressure which maintains this "inter-lockage" until the connecting rod 14 passes "dead center" position in the direction of rotation indicated in Fig. 11. Return movement of the carriage 36 results in the compressed spring means 63 accomplishing a snap action in the return of the parts to the relative positions in Fig. 4, as it becomes free at this stage to strongly exert the force which acts against the pin 59 to pivot the rocker 42 rearwardly. This action, together with the composite movement effected by the rocking of the rocker 42 as indicated by the arrow 55, are instrumental in minimizing wear of the serrations on the teeth 67, 68, whereby long life and interlocking accuracy are attained.

It can also be seen that, upon the return stroke of the connecting rod 14, which begins after it passes "dead center" position, the spring 46 can elongate as the carriage assembly of carriage 36 and abutments 47, 47' move rearwardly.

Broadly this invention considers a nut cracking machine having an improved conveyor system, and an arrangement of the die assembly which automatically accommodates the difference in amount of resiliency between long and

short nuts by providing a longer cracking travel for the more resilient, longer nuts, thereby insuring that substantially the same degree of final rupturing occurs for both long and short nuts.

5 The invention claimed is:

1. In a nut cracking machine, a conveyor movable in a closed path in a vertical plane, said conveyor including a series of spaced nut carriers each having a nut receiving cavity therein open at opposite ends to receive reciprocatory nut cracking dies during movement of the conveyor, there being a side opening to each of said cavities on the upper side of the carriers as they move downwardly with the conveyor, each of 10 15 said carriers having a nut elevating projection thereon proximate but facing opposite said cavity, said projections being adapted to lift nuts in succession during their upward travel and to discharge the nuts by gravity into the cavities of the next preceding carriers respectively as the carriers move successively from upward travel to downward travel.

2. For installation at spaced apart intervals on a chain conveyor adapted to move in a closed path in a vertical plane, the combination of, a 25 nut carrier comprising, a body, means on said body for attaching the body to said conveyor chain, there being a cavity in the body open at its ends to receive reciprocatory nut cracking dies during movement of the conveyor, and open 30 on one side thereof, a nut lifting projection extending outwardly from said body proximate but opposite said cavity, said projection having a nut receiving depression therein opposite said cavity and being adapted to lift the nut and to discharge the nut by gravity into the cavity of the next preceding carrier.

3. In combination with a conveyor adapted to convey nuts singly into position to be cracked, a 40 frame, a die fixed to said frame and adapted to receive therein an end of a nut to be cracked, a carriage assembly slidably mounted on said frame, said carriage assembly including a carriage and an abutment means, a drive wheel means, means connecting said wheel means to reciprocate said carriage in said frame upon each revolution of said wheel means, a movable die 45 slidably mounted on said carriage and adapted to receive in the forward end thereof the other end of said nut to be cracked, a spring bearing rearwardly against said abutment means and forwardly urging said movable die toward said fixed die, said movable die having a row of teeth therein extending outwardly and forwardly at an 50 angle to the direction of travel of said carriage, a pawl having a row of teeth therein shorter than said die row and adapted to mesh with said die teeth, mounting means slidable upon said carriage and adapted to support said pawl for movement away from, and into tooth engagement with said movable die, a stop, a head to contact said stop, spring means to bear forwardly against said head and to urge rearwardly against forward movement of said pawl, said mounting 55 means including means adapted to receive said head and said spring means therein, the forward motion of said carriage assembly first bringing said head against said stop so that said spring means urges against forward progress of 60 said mounting means, said drive wheel means being adapted to drive said conveyor to deliver said nut into die grasped position as further forward movement of said carriage assembly brings said movable die against said nut to arrest further movement of said movable die so that fur- 65 70 75

ther forward carriage assembly movement compresses said spring, said spring means also being compressed as said stop bears against said head causing said mounting means to slide to position said pawl teeth in locked engagement with said die teeth, and final forward movement of said carriage assembly with said mounting means interlocked therewith resulting in further compression of said spring means between said head and said pawl as said movable die moves further forward to crack said nut.

4. In combination with a conveyor adapted to convey nuts singly into position to be cracked, a frame, a die fixed to said frame and adapted to receive therein an end of a nut to be cracked, a carriage assembly slidably mounted on said frame, said carriage assembly including a carriage and an abutment means, a drive wheel means, means connecting said drive wheel means to reciprocate said carriage means in said frame upon each revolution of said wheel means, a movable die slidably mounted on said carriage and adapted to receive in the forward end thereof of the other end of said nut to be cracked, a spring bearing rearwardly against said abutment means and forwardly urging said movable die toward said fixed die, said movable die having a row of teeth therein extending outwardly and forwardly at an angle to the direction of travel of said carriage, a pawl having a row of teeth therein shorter than said die row and adapted to mesh with said die teeth, a carrier plate slidably with relation to said carriage, a rocker pivotally mounted on said carrier plate and adapted to pivotally support said pawl, a stop, a head to contact said stop, a pin, spring means to bear forwardly against said head and to urge rearwardly against said pin to force said pin against said pawl, said carrier plate providing means to receive said head, said spring means, and said pin therein, said carrier plate being slidable upon said carriage and adapted to support said pawl for movement away from, and into tooth en-

gagement with said movable die, and adapted to receive said head and said spring means therein, the forward motion of said carriage assembly first bringing said head against said stop so that said spring means urges against forward progress of said pawl, said rocker, and said carrier plate, said drive wheel means being adapted to drive said conveyor to deliver said nut into die grasped position as further forward movement of said carriage assembly brings said movable die against said nut to arrest further movement of said movable die so that further forward carriage assembly movement compresses said spring, said spring means also being compressed as said stop bears against said head causing said rocker to rotate, said rotation moving said pawl teeth into engagement with said die teeth, and final forward movement of said carriage assembly with said teeth in engagement resulting in further compression of said spring means between said head and said pawl as said movable die moves further forward to crack said nut.
